UNITED STATES PATENT OFFICE.

JOHN HOFMANN, OF BERKELEY, CALIFORNIA.

TOY.

Application filed April 7, 1920. Serial No. 371,928.

To all whom it may concern:

Be it known that I, JOHN HOFMANN, a citizen of the United States, residing at Berkeley, in the county of Alameda and State of California, have invented a new and useful Improvement in Toys, of which the following is a specification.

This invention relates to a toy.

It is the principal object of the present invention to provide a toy which will afford considerable amusement, at the same time requiring skill in its operation.

The present invention contemplates the use of a manikin head so designed as to be placed over the hand and thereafter manipulated to open and close its mouth, the mouth of said figure carrying a cord of resilient material to which a ball is fastened and which ball may be caught within the mouth of the manikin at the rebound of the cord.

The invention is illustrated by way of example in the accompanying drawings, in which:

25 Figure 1 is a view in front elevation showing one form of the present invention.

Fig. 2 is a view in central vertical section through the toy showing the way in which it is mounted over the hand of the operator.

30 In the drawings, 10 indicates a manikin head. This head is preferably made of papier mâché or other like material. The head of the manikin is formed in one piece which is supplemented by a lower jaw portion 11 adapted to complete a mouth 12.

35 This jaw portion comprises a lower lip, the chin and throat, which latter part is adapted to move in and out from in the rear of a front portion 13. The jaw is pivoted to

40 opposite sides of the head at points 14. By reference to Fig. 2 it will be seen that the mouth is formed with inturned lips 15 which provide recesses above and below the mouth into which the fingers and thumb of a hand

45 may be placed and by which the mouth may be opened and closed. In the drawings forming a part of this specification the head has a grotesque appearance although it will be understood that other designs might be

50 adopted such as animal figures and the like. A skirt portion 16 hangs from around the neck of the manikin and is intended to form a cover for the arm of the operator as well

55 as give the appearance of clothes for the figure. Fixed to the upper lip of the manikin is an elastic cord 17 which may be of

considerable length and which carries a ball 18 at its opposite end; this ball is preferably of soft rubber which might strike the face of the manikin without damage.

60 In operation of the present invention, the hand of the operator is inserted into the manikin head and disposed with the thumb beneath the lower lip flange of the lower jaw and the fingers on top of the upper lip flange. In this position the mouth may be readily opened and closed by the operation of the hand. It is intended that the cord 17 with the ball 18 shall be free to permit rebound and it is thus the principal object of 65 the toy to skillfully manipulate the mouth of the head and the ball so that the ball may be caught within the mouth when it rebounds. A free band 20 is stretched across within the head from pivot point 14 to pivot point 70 75 14. This band may be used when the operator has a small hand in which case the band will lie across the back of the hand.

75 It will thus be seen that this invention, while decidedly simple and inexpensive as to manufacturing costs may be used to afford considerable amusement as a toy.

80 While I have shown the preferred form of my invention as now known to me, it will be understood that various changes in the 85 construction, combination, and arrangement of parts may be made by those skilled in the art without departing from the spirit of the invention as claimed.

Having thus described my invention, what 90 I claim and desire to secure by Letters Patent, is:

1. A toy comprising a hollow figure head wherein the hand of an operator may be inserted, a lower jaw portion pivotally connected to the head, an inturned upper lip on the head for the reception of the ends of the operator's fingers, an inturned lower lip on the jaw portion for the reception of the end of the thumb of the operator and a band extending across the inside of the head and adapted to bear against the hand of the operator.

2. A toy comprising a hollow figure head adapted to receive the hand of an operator, 105 the said head including the cranium, base portions of the skull and a portion of the neck, when constructed in human shape, a jaw member including the chin and the remainder of the neck pivotally connected to 110 the head portion, the neck portion of the jaw member being extended into the neck por-

tion of the head member whereby it will swing therein when operated by the hand of the operator.

3. A toy comprising a hollow manikin head adapted to be positioned over the hand of an operator, a moving jaw forming a part of said head and adapted to be manipulated by the hand of the operator, upon which the manikin is mounted, a resilient cord secured to the manikin head and a ball carried by the opposite end of the cord and adapted to pass through the mouth of the manikin when the mouth has been opened and to be caught in the hand of the operator.
- 10 15. 4. A toy comprising a manikin having a hollow head of sufficient dimensions to receive the hand of an operator, a movable lower jaw pivoted to said head and provides

means engaged by the hand of the operator whereby the mouth of the manikin may be 20 opened and closed by movement of the operator's fingers, a rubber cord secured to the upper lip of the manikin head, and a resilient ball secured to the other end of said cord, and adapted to pass through the opened 25 mouth of the manikin and to be caught in the hand of the operator when rebounding at the end of said cord, and when the mouth has been opened by the operator's hand.

In testimony whereof I have hereunto set 30 my hand in the presence of two subscribing witnesses.

JOHN HOFMANN.
